United States Patent Office

Des. 181,198
Patented Oct. 15, 1957

181,198

ARTIFICIAL BOUQUET

Grace W. Jamison, Morganton, and Helen Hayes Sherrill,
Hickory, N. C., assignors to Dolly Hosiery Mills, Inc.,
Valdese, N. C., a corporation of North Carolina

Application November 19, 1956, Serial No. 43,838

Term of patent 14 years

(Cl. D29—1)

FIG-2

Fig. 1 is a top plan view of an artificial bouquet showing my new design; and

Fig. 2 is an edge view thereof.

We claim:

The ornamental design for an artificial bouquet, substantially as shown.
